UNITED STATES PATENT OFFICE.

HOWARD D. COLMAN, OF ROCKFORD, ILLINOIS, ASSIGNOR TO BARBER-COLMAN COMPANY, OF ROCKFORD, ILLINOIS, A CORPORATION OF ILLINOIS.

BOBBIN SKEWER.

Original application filed January 4, 1917, Serial No. 140,561. Divided and this application filed November 19, 1926. Serial No. 149,346.

In Patent No. 1,267,977, granted to me May 28, 1918, there is disclosed a machine for rewinding yarn from bobbins to form cheeses. The bobbin being unwound lies upon its side in a bobbin pocket or holder, and revolves as the yarn is drawn off from the side of the bobbin.

There are advantages in drawing yarn off the end of the bobbin. This, however, requires that the bobbin be firmly held by its butt end so that it cannot turn or rise.

The object of the present invention, generally stated, is to provide means in the nature of a skewer upon which the bobbin may be supported and firmly held against turning or rising as the yarn is drawn off the end of the bobbin at high speed.

A particular object of the invention is to provide means of the character stated which shall require a minimum of effort or attention on the part of the operator.

This application is a division of my application Serial No. 140,561, filed January 4, 1917 (now Patent No. 1,611,890, dated December 28, 1926).

In the accompanying drawings,

Figure 1 is a vertical sectional view illustrating one embodiment of my invention.

Fig. 2 is a transverse section of the skewer taken in the plane of line 2—2 of Fig. 1.

While the invention may be employed in connection with bobbins of various types, I have herein shown ordinary warp bobbins with yarn wound thereon with the so-called "warp wind," wherein the yarn is wound upon the bobbin in concentric cylindrical layers, as distinguished from the "filling wind," wherein the yarn is wound upon the bobbin in successive conical layers. Warp-wound yarn may be successfully drawn off the end of a bobbin at greater speed than filling-wound yarn.

The bobbins *a* are supported in a magazine which may be of any suitable construction, that herein shown comprising a disk 2 having a hub 3 which is fixed upon a vertical spindle 4. Said spindle is rotatably mounted in bearings 6 and 7 in the supporting framework. Means of any desired character may be provided for rotating the magazine step by step as required to move a spent bobbin out of running position and place a reserve bobbin in running position. The magazine comprises skewers 8 on which the

bobbins are supported in vertical position. 55 Each skewer consists of a plurality of longitudinal sections 9 movable radially in and out to clamp and release the bobbin. A contractile ring 10 (consisting of a coiled spring) encircling the lower portions of the 60 segments 9 tends to draw the segments together. The skewer has an annular shoulder 11 upon which the butt of the bobbin may stand. Above the shoulder 11 the skewer is provided with two annular surfaces 12 and 13 adapted to engage the walls of the bore of the bobbin when the skewer is expanded, the surfaces 12 and 13 being spaced apart in order that the bobbin shall be gripped at two separated places and thus 70 be firmly and concentrically held at each of those places. The means for expanding the skewer comprises a pin 14 mounted in a tubular guide 15 carried by the plate 2. The upper end of the guide 15 is upwardly 75 tapered as at 16, and fits within the correspondingly tapered lower end of the skewer. The upper end of the pin 14 has a downwardly tapering surface 17 adapted, when the pin 14 is moved downwardly, to 80 force the upper ends of the segments 9 apart and thus cause the skewer to engage the bobbin. A coiled expansive spring 18 surrounds the pin 14 within the guide 15 and bears against an annular shoulder 19 on the 85 pin. It will be seen that the spring 18 tends to cause the tapered surface 17 to enter between the upper ends of the segments 9 and also tends to move the skewer bodily downward over the tapered surface 90 16, the result being to expand the skewer into clamping engagement with the interior walls of the bobbin. Inasmuch as the skewer comprises the clamping portions 12 and 13 which are movable by the conical 95 surfaces 16 and 17 until they come into contact with the interior walls of the bobbin, the skewer is capable of firmly clamping bobbins having bores of various sizes and tapers.

The skewers are caused to clamp and release the bobbins in the rotation of the magazine by means of a cam flange 20 on the bracket that supports the bearings 6 and 7. The low portion of the flange 20 is indicated at 21 in said figures, the portion 21 being joined to the elevated portion of the flange by the inclines 22, only one of which inclines

is shown in the drawing. In the rotation of the magazine the pins 14 are moved around on the flange 20. When the pins are on the elevated portion of the flange, the skewer is 5 in the contracted condition shown at the right-hand side of Fig. 1. When the pins 14 are above the low portion 21, the skewers are in the expanded or clamping condition shown at the left-hand side of Fig. 1.

10 In use, the operator places a bobbin on a skewer 8 while the latter is above the high portion of the cam flange 20. When the skewer reaches a position above the low portion of the cam flange, the skewer is automatically actuated to clamp or lock the bobbin against rotation or upward movement as the yarn is being drawn off the upper end of the bobbin. When the yarn is drawn off at high speed, the yarn balloons and thus 20 swings clear of the yarn mass, and the tip of the bobbin, even when the yarn extends from the lower portion of the yarn mass. By using warp-wound bobbins and supporting them by means firmly engaging the butt, it 25 is possible to rewind at very high speed and under low tension.

It will be apparent that the bobbin-supporting and locking means herein disclosed requires a minimum of attention and effort 30 on the part of the operator. The skewer enters only the lower portion of the bobbin bore, hence the bobbin and the skewer can be engaged and disengaged by means of a relatively short movement. Notwithstanding 35 the short hold which the skewer has on

the bobbin, the latter is firmly held, since the bobbin is gripped at two separated points.

The invention is susceptible of embodiment in various forms within the scope of 40 the appended claims.

I claim as my invention:

1. A skewer for supporting a yarn carrier and adapted to enter only the lower end of the carrier, said skewer having, in combination, a plurality of longitudinal segments, a contractile ring encircling the segments, and means for separating the segments to expand the skewer into clamping engagement with the carrier at two longitudinally separated points. 45 50

2. A skewer for supporting a yarn carrier and adapted to enter only the lower end of the carrier, said skewer having, in combination, a plurality of longitudinal segments, and a member movable into place between said segments to force the latter outwardly 55 into clamping engagement with the carrier at two longitudinally separated points.

3. A yarn-carrier support consisting of a relatively short skewer adapted to enter only the lower end of the yarn carrier, internal means for expanding the lower end of the skewer into engagement with the carrier, and internal means for expanding the upper 60 65 end of the skewer into engagement with the carrier.

In testimony whereof, I have hereunto affixed my signature.

HOWARD D. COLMAN.
